DESIGN FOR A CARBONATOR

Elwyn A. Arnold, San Francisco, Calif.

Application April 5, 1939, Serial No. 84,045

Term of patent 7 years

To all whom it may concern:

Be it known that I, Elwyn A. Arnold, a citizen of the United States, residing at the city and county of San Francisco, State of California, have invented a new, original, and ornamental Design for a Carbonator, of which the following is a specification, reference being had to the accompanying drawing, forming part thereof.

In the drawing:

Fig. 1 is a front elevational view of a carbonator embodying my new design;

Fig. 2 is a side elevational view thereof, looking in the direction indicated by arrows 2—2 in Fig. 1;

Fig. 3 is a rear elevational view thereof, looking in the direction indicated by arrows 3—3 in Fig. 2;

Fig. 4 is a top plan view thereof, looking in the direction indicated by the arrows 4—4 in Fig. 1; and

Fig. 5 is a bottom plan view thereof, looking in the direction indicated by arrows 5—5 in Fig. 3.

I claim:

The ornamental design for a carbonator, substantially as shown and described.

ELWYN A. ARNOLD.
